W. Evans,

Organ Swell,

N° 17,501.

Patented June 9, 1857.

Fig: 1.

Fig: 2.

UNITED STATES PATENT OFFICE.

WILLIAM EVANS, OF LOCKPORT, ILLINOIS.

MELODEON.

Specification of Letters Patent No. 17,501, dated June 9, 1857.

To all whom it may concern:

Be it known that I, WILLIAM EVANS, of Lockport, in the county of Will and State of Illinois, have invented a new and useful Improvement in Melodeons; and I do hereby declare that the following is a full, clear, and exact description of the same, reference being had to the accompanying drawings, forming a part of this specification, in 10 which—

Figure 1 is a transverse vertical section of those parts of the instrument which require to be shown to illustrate my invention. Fig. 2 is a plan of the same.

15 Similar letters of reference indicate corresponding parts in both figures.

This invention relates to melodeons in which the exhaustion bellows is used.

It consists in arranging the swell to close 20 by a movement upward or away from the reed tubes instead of by a movement downward or toward the reed tubes.

By this new arrangement and mode of operation several very important results are 25 effected as will be hereinafter explained. I will first however describe with reference to the drawings the manner in which the invention is applied.

A is the reed board; (a) one of the reed 30 tubes; (b) one of the reeds; and B the reflecting board, all of which occupy the same positions as in the melodeons with exhausting bellows now in general use.

C is the swell hinged in the usual manner 35 to the back edge of the reed board A.

D is the stop on the reflecting board B, against the under side of which the swell closes with an upward movement, the said under side being placed rather higher than 40 the top of the reed board, and being faced with velvet so that the swell may fit tightly against it.

(c) is the spring by which the swell is 45 closed consisting of a piece of flat steel similar to clock spring secured to the top of the reed board by a screw (d), and passing through the hinge of the swell and bearing against the under side of the same.

E, F, are two levers by whose agency the 50 swell is opened, the former E, which is of the second order, being arranged close to one side of the case on a fulcrum pin (e) and resting on an arm (f) attached to one end of the swell, and the latter F which is 55 of the first order, being arranged close to

the back of the case on a fulcrum pin (g) with one end resting on the rear end of E and the other end connected with a treadle that is not shown.

The swell when arranged as above described to close upward enlarges the chamber formed between itself and the reeds as it closes instead of diminishing it as it does when it closes downward upon the board G in the old way and it opens with the current 60 of air instead of in opposition to it.

By the old arrangement when the swell is closed the tone of the lower or large reeds is considerably flattened while that of the higher or smaller ones is less so, as that 70 part of the chamber opposite the smaller reeds is not diminished so much in proportion to the size of its reeds and tubes as the part opposite the larger ones, and hence when the swell is closed the instrument is 75

“out of tune”, the lower notes being too flat for the higher ones. This is not the case, or at any rate not perceptibly so, when the swell closes upward and enlarges the 80 chamber, but the instrument will produce

the softest tones possible and still remain in tune. In fact with my arrangement of the swell the character of the tone of the instrument is different to that of melodeons generally and more like that of the “open 85

diapason” of the organ. The tone is rich and mellow and extremely soft when the swell is closed, and when the swell is open the tone is very full but still as deep and 90

mellow as when it was closed, while in melodeons with the old arrangement of the swell, the tone is more piercing and harsh when the swell is open than when it is closed. Another result obtained by my arrangement of the swell is that the tone of 95

the treble reed does not tremble with the movement of the left hand on the bass keys when the swell is closed as it does with the old arrangement. Again my arrangement affords facility for getting at the reeds to 100

remove any dirt that may interfere with their vibration, or to examine, repair or tune them, by fitting the reflecting board to drop into two grooves (h), one of which is shown in Fig. 2, where a part of the said board is 105 omitted for the purpose, the lifting up of the board B out of its place, with the stop piece D against which the swell closes attached, exposes all the reeds to view—the swell being already raised out of the way.

110

What I claim as my invention and desire to secure by Letters Patent, is:

1. The arrangement of the swell to close by a movement upward or away from the reed tubes substantially as specified, instead of downward or toward the reed tubes in the heretofore usual manner for the purposes herein specified.

2. And I also claim the stop D against

which the swell closes, attached to the reflecting board so as to be removed therewith to leave the reeds exposed as herein described.

WILLIAM EVANS.
